UNITED STATES PATENT OFFICE.

FRANK S. RODE, OF JEANNETTE, PENNSYLVANIA.

DESIGN FOR A GAME BOARD.

Application filed January 18, 1923. Serial No. 4,931. Term of patent 7 years.

To all whom it may concern:

Be it known that I, FRANK S. RODE, a citizen of the United States of America, residing at Jeannette, in the county of Westmoreland and State of Pennsylvania, have invented a new, original, and ornamental Design for Game Board, of which the following is a specification, reference being had to the accompanying drawing, forming part thereof.

The figure is a view in perspective of a game board, showing my new design.

I claim:—

The ornamental design for a game board, as shown.

FRANK S. RODE.
